UNITED STATES PATENT OFFICE.

CHARLES CLARANCE DAVIS, OF RICHMOND, VIRGINIA.

CHAIN.

1,421,178.

Specification of Letters Patent. Patented June 27, 1922.

Application filed July 28, 1920. Serial No. 399,644.

To all whom it may concern:

Be it known that I, CHARLES C. DAVIS, a citizen of the United States, residing in Richmond, Henrico County, Virginia, have 55 invented certain Improvements in Chains, of which the following is a specification.

My invention relates to certain improvements in conveying, or carrying, chains of the roller type, which travel on rails and 10 pass around sprocket wheels that are driven.

The object of my invention is to design the links of the chain so that the rollers will at all times bear upon the rails, even when the rollers have been reduced by excessive 15 wear, the rollers traveling on the rails on the carrying and on the return runs.

In the accompanying drawings:

Fig. 1 is a side view of a portion of a chain illustrating my invention; 20 Fig. 2 is a sectional view on the line 2—2, Fig. 1, showing the chain on the carrying run; and

Fig. 3 is a sectional view, showing the chain on the return run.

1 is a rail arranged to support the chain on the carrying run. 2 is a rail arranged to support the chain on the return run. The chain consists of a series of links 3 connected together by pivot pins 4, clearly 30 shown in Fig. 1. Each link is made in two parts and the side members are greater in width at one end than at the opposite end so that the side members of one link overlap the side members of an adjoining link, as clearly shown in Figs. 1 and 2. The pivot pins 4 are riveted to form heads which retain the links in proper alignment. Each section of each link, in the present instance, has a curved socket 5 for the reception of a 40 stick 6, as shown by dotted lines in Fig. 1, on which material can be hung, as, in the present instance, the chain is used for carrying material through a drying apparatus.

Each section of each link has an extension 45 7 forming a bearing surrounding the pivot pin 4, as shown in Fig. 2, and mounted on the extensions 7 are the rollers 8, which travel on the rails 1 and 2. It is the usual practice to make the links of the chain so 50 that they are above the upper surface of the carrying rail. The rail is usually made

wider than the chain, consequently, as the rollers wear, the links are allowed to come in contact with the upper surface of the rail and to rub on the rail, materially increasing the friction.

By my invention, I design the chain and the rails so that the chain is carried at all times by the rollers, irrespective of the extent of wear.

60 Each link has a depending portion 9, which extends on each side of the narrow rail 1, as clearly shown in Fig. 2. These portions 9 tend to retain the rollers in proper position on the carrying rail 1, dispensing with other guides and allowing the rollers to bear at all times upon the rail, as the links of the chain are clear of the rail. These extensions strengthen the links.

65 The chain passes around a sprocket wheel 70 at one end of the run. The extensions, in which the sockets 5 are formed, act as guides on the return run, as shown in Fig. 3. In some instances, the chain may be composed of alternated plain and socketed links, and 75 some of the links may have the extensions 8, while other links may be plain.

I claim:

1. The combination of a narrow rail; a chain adapted to travel over said rail, said 80 chain consisting of a series of links pivotally connected, the side members of the links being spaced apart a greater distance than the width of the rail and extending on each side of the rail; and a single series of rollers 85 mounted on the pivots of the links of the chain and bearing upon the rail.

2. The combination of a narrow rail; a chain consisting of a series of links pivotally connected, each link being made in 90 two parts and forming side members, the side members of each link being spaced apart a greater distance than the width of the rail, each link having an extension at the pivot; a rivet passing through the extensions of the links and through the side members of an adjoining link; and a roller mounted on the opposite extensions of each link, said roller being of a greater width than the rail, the side members of each link 100 extending on each side of the rail.

CHARLES CLARANCE DAVIS.
